LIFTING DEVICE

John Charles George Speller, Kenton, England,
assignor to Ealing Studios Limited, Ealing, London, England

Application September 26, 1947, Serial No. 776,293
In Great Britain June 19, 1947

15 Claims. (Cl. 254—8)

1

This invention relates to lifting devices and is eminently suitable for lifting flat and relatively high articles which have to be transferred from one place to another such for example as film sets and the like which are placed in a temporary position and then have to be transported to another position. The principal object of the invention is to provide an improved lifting device which is simple in construction, easily movable, and by one person.

In order that the invention may be more easily understood and readily put into practice, an embodiment thereof will hereinafter be described with reference to the accompanying drawings in which—

Figure 1 shows a perspective view of the device,

Figure 2 shows a side elevation of Figure 1,

Figure 3 shows an end elevation of Figure 1,

Figure 4 shows a plan view of the device, and

Figures 5a, 5b, 5c and 5d show fragmentary views of the resting, first lift and maximum lift positions of the lifting bar.

Referring to Figures 1 to 4, the framework comprises a base 1, built up from angle bars, riveted, welded or otherwise secured together, of substantially triangular shape in plan. Suitably secured to the apex 2 of the base are a pair of angle members 3, 4. These members are bent, as shown in the drawing, so that the member 3 may be secured to one corner 5 of the base and the member 4 to the corner 6 thereof. The upper end of the framework is strengthened by a plate 7 which also constitutes a bearing for a pivot pin 8 for a lever 9. Further bracing members 10 may also be provided so that a strong, rigid and comparatively light framework may be constructed. Castors 11 are suitably mounted on the framework so that the lifting device is made mobile.

The lever 9, as hereinbefore stated is pivoted to the framework on the pivot pin 8 and the front end of the lever is pivoted at 12a to a channel section lifting bar 12, the other end carrying a counterweight 13. At its lower end the lifting bar 12 is formed with guide slots 14 in its side flanges, through which passes a pivot pin 15, carried in brackets 16 secured to the framework. A roller 17 provided on the pin 15 engages the inside face of the bottom of the channel of lifting bar 12 to minimise friction as bar 12 moves up or down. At, or near, the top and bottom of the bar 12 are provided hook members 18, 19 which engage the article to be lifted as hereinafter to be described.

Pivots secured to the lever 9 at the weighted end thereof, are a pair of links 20, 21 forming a

2

toggle joint, the two links being pivoted together at 22. The link 21 is constructed in the form of a bell-crank the upper part thereof carrying a handle 23 and the lower end is pivoted to the framework at 24. A check lever 25 is provided on the framework the outer end thereof being removably secured to the arm 21 of the toggle by means of a removable pin 26. This lever 25 maintains the toggle arms 20, 21 towards their aligned position when desired.

The framework has a hole 27 into which a loose pin 28 is inserted to limit the upward lift of the bar 12, and a fixed pin 29 to give a different limit.

Referring now to Figures 5a, 5b, 5c and 5d the reference 30 represents the article to be lifted. On reference to Figure 5a it will be seen that the hook members 18, 19 are about to engage the article 30 and in this position the bar 12 is leaning slightly forward at the top. It will also be seen that the pin 15 is in position at the top of the slot 14. At the commencement of the lift the bar is vertical, Figure 5b. In Figure 5c the bar has commenced to move upwardly and finally, when the bar reaches its top position, that is the position of maximum lift, it is leaning slightly backwards as shown in Figure 5d. This movement is caused by pivoting the top end of the bar 12 to the lever 9 and forcing the lower end to pivot and slide in the slots 14, and co-relating the relative position of the hooks and the part of the article to be lifted, with which the hooks engage.

The device is eminently suitable for use in lifting film sets or scenery. Such sets are usually constructed from a framework of battens and the hook members 18, 19 are conveniently positioned on the bar to engage a pair of such battens. Assuming it is desired to lift and transport a film set, the check lever 25 is positioned as shown in the drawings thereby holding the toggle arms towards their aligned position and holding the counterweight in its uppermost position and the bar 12 in its lowermost position. The device is then wheeled so that the hooks are under the battens as shown in Figure 5a. The loose pin 29 is placed in the hole 27 and the pin 26 is removed to free the toggle arm from the check lever 25.

This will allow the toggle arms 20, 21 to move to the left as viewed in Figure 2 when the handle is depressed, the said handle at the same time lowering the counterweight 13 thereby turning the lever 9 on its pivot and lifting the bar 12 until the hooks 18 and 19 engage the battens.

The counterweight is of such size that it will lift a predetermined maximum load so that if the

set piece to be lifted is within the maximum load the weight will fall and lift the set piece, which may then be moved to its new position.

If it is found that the weight of the set piece is greater than the maximum load capable of being lifted by the counterweight then a second lifting device is attached in the same manner to the set piece so that the lifting capacity of the device is doubled. Any number of lifting devices may be so attached to the set piece so that the lifting force of the combined counterweights is greater than the weight of the set piece to be lifted.

By arranging the bar 12 to incline inwardly the set will have less tendency to swing or fall off the hooks 18, 19. In order to steady the set, forwardly projecting abutments 31 are provided on the front of the frame, the front faces of which are disposed on the same vertical plane as that of the lifting bar 12. When it is desired to lower the set, the handle 23 is raised to move upwardly bringing the toggle levers 20, 21 towards their aligned position. This will turn the lever 9 on its pivot and lower the bar 12. Continued upward movement of the handle 23 will move the toggle levers towards their aligned position so that the check lever can be replaced. In this position the set will be resting on the floor and the hooks will be free of the battens, the device may then be removed.

Although the device has been described for use for lifting film sets or scenery, it will be understood that it is not limited to this particular purpose as articles other than film sets, such for example as temporary wall sections, or similar articles, may also be lifted thereby.

I claim:

1. Lifting apparatus including in combination a mobile framework, a substantially vertical lifting bar member mounted at the front of said framework for substantially vertical movement therein, engaging means on said lifting bar for engagement with an article to be lifted, a leverage multiplying device, a counterweight transmitting lifting force to said lifting bar through said leverage multiplying device, and means for exerting force upwardly on said counterweight.

2. Lifting apparatus according to claim 1 wherein a lever arm carrying the counterweight has one link of a toggle pivoted thereto the other link of said toggle being pivoted to the frame below said lever arm whereby by moving said toggle towards its straightened position the counterweight can be raised to lower the lifting bar.

3. Lifting apparatus including in combination a framework a plurality of wheels carrying said framework, a substantially horizontal actuating lever carried by said framework and fulcrummed between its ends within the horizontal area of the wheel base of the framework, a substantially vertical lifting bar member mounted at the front of the framework, hooks carried by said lifting bar member for engagement with the article to be lifted, said lifting bar being pivoted at its upper end to the forward end of said actuating lever, and pivoted at its lower end to the framework for vertical sliding movement relative thereto, the position of the lower pivot being so selected with relation to the position of the pivot connecting the lifting bar to the actuating lever that when the said lifting bar is in its lowermost position it is leaning slightly forward away from the framework at the top, whereas when in its highest position said lifting bar is leaning

slightly backwards towards the framework at the top, a counterweight acting on the actuating lever to lift said lifting bar, and means for exerting force upwardly on said counterweight to raise it when required.

4. Lifting apparatus according to claim 3 wherein a lever arm carrying the counterweight has one link of a toggle pivoted thereto the other link of said toggle being pivoted to the frame below said lever arm whereby by moving said toggle towards its straightened position the counterweight can be raised to lower the lifting bar.

5. Lifting apparatus including in combination a mobile framework, a substantially vertical channel section lifting bar having the inside of the channel facing the frame, hook members carried on the outside of the channel bottom for engagement with the article to be lifted, a leverage multiplying device, a counterweight transmitting lifting force to said lifting bar through said leverage multiplying device, and means for exerting force upwardly on said counterweight.

6. Apparatus for forming film sets according to claim 5 wherein a lever arm carrying the counterweight has one link of a toggle pivoted thereto the other link of said toggle being pivoted to the frame below said lever arm whereby by moving said toggle towards its straightened position the counterweight can be raised to lower the lifting bar.

7. Lifting apparatus including in combination a framework, a plurality of wheels carrying said framework, a substantially horizontal actuating lever carried by said framework and fulcrummed between its ends within the horizontal area of the wheel base of the framework, a substantially vertical channel section lifting bar member having the inside of the channel facing the frame and mounted at the front of the frame, hook members carried on the outside of the channel bottom for engagement with the article to be lifted, said channel member being pivoted at its upper end to the forward end of said actuating lever, slots in the sides at the lower end of said channel member, a pivot pin carried by said frame and passing through said slots to provide vertical sliding movement for the said channel member relative to said frame, a roller carried by said pivot pin for engagement with the inside face of said channel bottom to minimise friction, the position of the lower pivot being so selected with relation to the position of the pivot connecting the channel member to the actuating lever that when the said channel member is in its lowermost position it is leaning slightly forward away from the framework at the top, whereas when in its highest position said lifting bar is leaning slightly backwards towards the framework at the top, a counterweight acting on the actuating lever to lift said lifting bar, and means for exerting force upwardly on said counterweight to raise it when required.

8. Lifting apparatus including in combination a mobile framework, a substantially vertical channel section lifting bar having the inside of the channel facing the frame, hook members carried on the outside of the channel bottom for engagement with the article to be lifted, said channel having slots formed in its sides, a pivot pin carried by said frame and passing through said slots, a roller on said pivot pin engaging the inside face of the channel bottom to minimise friction, a leverage multiplying device, a counterweight transmitting lifting force to said lifting bar through

said leverage multiplying device, and means for exerting force upwardly on said counterweight.

9. Lifting apparatus including in combination a mobile framework, a substantially vertical lifting bar member mounted at the front of said framework for substantially vertical movement therein, engaging means on said lifting bar for engagement with an article to be lifted, abutments carried by said framework projecting forwardly to either side of said lifting bar, said abutments having flat front faces disposed in the same vertical plane as that of the lifting bar to engage and steady the article to be lifted, a leverage multiplying device, a counterweight transmitting lifting force to said lifting bar through said leverage multiplying device, and means for exerting force upwardly on said counterweight.

10. Lifting apparatus including in combination a mobile framework, a substantially vertical lifting bar member mounted at the front of said framework for substantially vertical movement therein, engaging means on said lifting bar for engagement with an article to be lifted, a leverage multiplying device, a counterweight transmitting lifting force to said lifting bar through said leverage multiplying device, a lever arm carrying the counterweight, a toggle having one link pivoted to said lever arm, the other link of said toggle being pivoted to said framework below said lever arm whereby by moving said toggle towards its straightened position the counterweight can be raised to lower the lifting bar, and means for exerting force upwardly on said counterweight.

11. Lifting apparatus including in combination a framework, a plurality of wheels carrying said framework, a substantially horizontal actuating lever carried by said framework and fulcrummed between its ends within the horizontal area of the wheel base of the framework, a substantially vertical lifting bar member mounted at the front of the framework, hooks carried by said lifting bar member, for engagement with the article to be lifted, said lifting bar being pivoted at its upper end to the forward end of said actuating lever, and pivoted at its lower end to the framework for vertical sliding movement relative thereto, the position of the lower pivot being so selected with relation to the position of the pivot connecting the lifting bar to the actuating lever that when the said lifting bar is in its lowermost position it is leaning slightly forward away from the framework at the top, whereas when in its highest position said lifting bar is leaning slightly backwards towards the framework at the top, a counterweight acting on the actuating lever to lift said lifting bar, and means for exerting force upwardly on said counterweight to raise it when required, abutments carried by said framework projecting forwardly to either side of said lifting bar, said abutments having flat front faces disposed in the same vertical plane as that of the

lifting bar to engage and steady the article to be lifted.

12. Apparatus for forming film sets according to claim 11 wherein a lever arm carrying the counterweight has one link of a toggle pivoted thereto the other link of said toggle being pivoted to the frame below said lever arm whereby by moving said toggle towards its straightened position the counterweight can be raised to lower the lifting bar.

13. Lifting apparatus including in combination a mobile framework, a substantially vertical channel section lifting bar having the inside of the channel facing the frame, hook members carried on the outside of the channel bottom for engagement with the article to be lifted, said channel having slots formed in its sides, a pivot pin carried by said frame and passing through said slots, a roller on said pivot pin engaging the inside face of the channel bottom to minimise friction, a leverage multiplying device, a counterweight transmitting lifting force to said lifting bar through said leverage multiplying device, and means for exerting force upwardly on said counterweight, abutments carried by said framework projecting forwardly to either side of said lifting bar, said abutments having flat front faces disposed in the same vertical plane as that of the lifting bar to engage and steady the article to be lifted.

14. Lifting apparatus including in combination a mobile framework, a substantially vertical lifting bar member mounted at the front of said framework for substantially vertical movement therein, engaging means on said lifting bar for engagement with an article to be lifted, a leverage multiplying device, a counterweight transmitting lifting force to said lifting bar through said leverage multiplying device, a lever arm carrying the counterweight, a toggle having one link pivoted to said lever arm, the other link of said toggle being pivoted to said framework below said lever arm whereby by moving said toggle towards its straightened position the counterweight can be raised to lower the lifting bar, and means for exerting force upwardly on said counterweight, abutments carried by said framework projecting forwardly to either side of said lifting bar, said abutments having flat front faces disposed in the same vertical plane as that of the lifting bar to engage and steady the article to be lifted.

15. Lifting apparatus according to claim 14 wherein a lever arm carrying the counterweight has one link of a toggle pivoted thereto the other link of said toggle being pivoted to the frame below said lever arm whereby by moving said toggle towards its straightened position the counterweight can be raised to lower the lifting bar.

JOHN CHARLES GEORGE SPELLER.
